GAS LIGHTING AND EXTINGUISHING APPARATUS.

1,271,274.

Specification of Letters Patent.

Patented July 2, 1918.

Application filed December 22, 1916. Serial No. 138,481.

To all whom it may concern:

Be it known that I, DANIEL CARTER, of the city of Toronto, in the county of York and Province of Ontario, Dominion of Canada, have invented certain new and useful Improvements in Gas Lighting and Extinguishing Apparatus; and I hereby declare that the following is a full, clear, and exact description of the same.

10 This invention relates to an apparatus by which the stop-cock of a gas light fixture may be opened and closed, and the object of the invention is to so construct and arrange this apparatus that the gas can be lighted 15 and extinguished at will, and the lapse of time for the extinguishing of the light predetermined.

In the drawings, Figure 1 is a sectional elevational view of the apparatus, showing 20 the position of the parts when the stop-cock controlling the flow of gas to the burner of the gas light fixture is closed. Fig. 1^a is a similar view, showing the position of the parts when the stop-cock is open. Fig. 25 2 is an elevational view, looking at the parts from the opposite side to Figs. 1 and 1^a. Fig. 3 is a modification of the construction shown in Figs. 1 and 2. Fig. 4 is a detail view of the air pump. Fig. 5 is a detail 30 view of the air chest. Fig. 6 is a perspective view of the ratchet wheel shown in Fig. 2. Fig. 7 is a perspective view of the actuator shown in Fig. 2. Fig. 8 is a detail view of the pawl, shown in Fig. 2. Fig. 9 is a detail 35 view of the inlet port for the air cylinder, showing it provided with a check valve. Fig. 10 is a fragmentary view of the lever and ratchet wheel shown in Figs. 1 and 2.

The pipe *b*, leading to the burner *a*, is 40 fitted with the usual rocking or rotary stop-cock *c*, controlling the flow of gas through the pipe to the burner, and with the usual pilot pipe *d* and pilot burner *e* for igniting the gas at the burner *a*, the stop-cock extending through the casing *f*, and being provided with an arm *g*, by which it is turned to respectively open and close the passage 45 through the gas pipe.

Clamped on the gas pipe is the bracket *h* of 50 an air cylinder *i*, consisting of a cylinder wall *i'* and cylinder heads *j* and *j'*, the air cylinder having, a hollow nipple *k* forming an air inlet port, and, a hollow nipple *l* forming an

exhaust port. In Figs. 1, 2 and 3, the inlet port is shown to extend through the cylinder head *j*, and in Figs. 1 and 2 the exhaust port is shown to extend from the nipple *k*, and in Fig. 3 to extend through the side of the air cylinder adjacent to the cylinder head *j*, and in both cases, the exhaust port is provided with an adjustable cap *l'* by which the escape of air through it may be regulated, but the location of the inlet and exhaust ports, and the means for the regulation of the latter, may be varied within the scope of the claims.

Within the air cylinder *i* is a piston *m*, having a piston rod *m'*, passing through the cylinder head *j'*, and coiled on the piston rod *m'*, between the piston *m* and the cylinder head *j'*, is a spring *n*, to press the piston in the direction of the cylinder head *j*.

In the wall of the air cylinder, adjacent to the cylinder head *j'* is a relief port *o*, through which the air in the cylinder, between the piston and cylinder head *j'*, may escape, when the piston is moving, from its starting position adjacent to the cylinder head *j*, to the completion of its stroke in the direction of the cylinder head *j'*; and about the middle of the cylinder wall is a relief port *o'* to relieve the pressure in the air cylinder between the piston and cylinder head *j* when its stroke in said direction is completed.

At the free end of the piston rod *m'* is a slotted knuckle *m''* by which the arm *g* is loosely connected with the piston rod, and connected with the arm *g* and with the burner is a spring *p*, by which the arm is tensioned, to close the valve and maintain it in its closed position when the piston rod is retracted within the air cylinder.

Connected with the nipple *k* and with a hollow connection *q''* of the air chest *q'* is an air duct *q*, and within the air chest *q'* is a spring pressed valve *r*, controlling the passage therefrom to the air duct. The valve *r* normally closes the passage through the hollow connection, and is opened by a plunger *r'* so that the air within the air chest *q'* may pass through the air duct *q* to the air cylinder *i*, and connected with the air chest *q'* is an air pump *t*, by which compressed air may be forced into the air chest.

When the plunger *r'* is pressed to lift the

valve r from its seat, the air pump may be operated to compress the air in the air chest and this air passes from the air chest into the duct g and air cylinder i , and forces the piston m toward the cylinder head j' . This movement of the piston compresses the spring n and effects the outstroke of the piston rod m' , which, through its knuckle connection with the arm g turns the stop-
cock c to open the passage through the gas pipe to the burner.

The piston m , under the pressure of the air in the cylinder between it and the cylinder head j , moves to the limit of its stroke in the direction of the cylinder head j' , and when it passes the relief port o' the compressed air in the cylinder between it and the cylinder head j begins to escape through the port o' thus partly relieving the pressure
on the piston.

When the operation of the air pump ceases, the plunger r' is released, and the valve r , under the influence of its spring r'' , then closes against its seat and shuts off communication between the air duct g and the air chest, the compressed air in the air cylinder between the piston and the cylinder head j continuing to escape through the port o' until the pressure on the piston and the valve r is fully relieved. When this pressure is relieved, the piston m automatically reverses its movement, under the influence of the spring n , and travels in the direction of the piston head j , until it covers the relief port o' , when its further movement in that direction is resisted, either by the creation of the air check in the cylinder, between the piston and the cylinder head j , or by mechanical means hereinafter described, the spring r'' being of sufficient tension to hold the valve r closed against its seat regardless of the pressure within the air cylinder, created either by the spring n or by the spring and air check.

During the reversal of the movement of the piston to cover the relief port o' the piston rod moves slightly inwardly into the cylinder, and to prevent the closing or partial closing of the stop-cock c during such movement, the knuckle m'' is formed with an elongated slot b'' to contain the arm g , the length of this slot being sufficient to allow for the movement of the piston to cover the relief port before movement is imparted to the arm g and the stop-cock c .

In Fig. 5 the air chest g' is shown to be provided, with several hollow connections g'' for the ducts g of a corresponding number of lighting fixtures each connection being controlled by a spring-pressed valve r actuated by a plunger r' and with a relief port s normally closed by a valve s' , opened by a plunger s'' . By opening the valve s' the air pump may be reversed without creating suction in the air chest, thus avoiding

any possibility of such operation of the air pump disturbing any previously operated piston or pistons, the advantage of this construction being that the stop-cocks, of any or all of the lighting fixtures, may be selectively opened and closed at will from a central station.

To close the stop-cock c , by the action of the air pump, the plunger r' is operated to open the valve r , which has the immediate effect of eliminating the air check in the air cylinder, the action of the pump then being reversed to exhaust the air from the duct and the air cylinder, and create sufficient suction therein to move the piston toward the cylinder head j , this suction being assisted by the spring n , which presses the piston m in the direction of the cylinder head j , until the piston completes its movement in that direction. This causes the in-stroke of the piston rod and brings the knuckle m'' into operative relation with the arm g for the closing movement of the stop-cock, this closing movement of the stop-cock being assured by the spring p , which not only maintains the valve in its closed position, but also assists its closing movement owing to the knuckle slot b'' .

In Fig. 3, the piston rod m' is shown to be provided with a loosely fitted collar u , slideable axially of the piston rod, and connected with the collar u is an actuator, comprising a crank arm u' , one member of which extends horizontally across the cylinder head j' , and the other member of which extends vertically from the horizontal member and is provided with a detent u'' . Extending across the cylinder head j' is a detent plate v , slotted at v' for the piston rod m' and at v'' for the crank arm u' . Connecting the detent plate v to the air cylinder i is a spring arm w , which permits of a yielding movement of the detent plate v in a direction from and toward the cylinder head j' , and adjustably secured to the detent plate v is a catch w' to be engaged by the detent u'' .

The crank arm u' is connected by a spring w'' to some convenient or appropriate part of the air cylinder i , the purpose of the spring being to normally hold the arm and collar in a retracted position, and, attached to the crank arm u' is a pull chain x by which the crank arm u' and collar u may be drawn downward. During the downward movement of these parts the collar u engages the knuckle m'' and causes the downward or outstroke movement of the piston rod m' with it, until the piston m is arrested by the contraction of the spring n , the piston rod m' being provided with a catch x' to engage the detent plate v and securely hold the piston rod in its outstroke position when the piston has moved to cover the relief port o' until the catch is disen-

gaged from the detent plate either by the manipulation of the pull chain or the reversal of the operation of the air pump.

When the strain on the pull chain x is released, the spring w'' returns the crank arm u' to its retracted position so that the detent u'' will engage the catch w' on the next downward movement of the crank arm, the collar u , during the retraction sliding freely upward on the piston rod, and the piston under the influence of the spring n moving toward the cylinder head j until it covers the relief port o' . During the outstroke of the piston rod m' the stop-cock c is turned, by the engagement of the knuckle m'' with the arm g , to open the passage through the gas pipe b to the burner a , and is held open while the piston rod m' remains at the limit of its outstroke. The gas then flows through the gas pipe to the burner and is ignited by the light from the pilot burner e , and continues burning while the stop-cock remains open.

When it is desired to close the stop-cock through the agency of the pull chain x , the latter is drawn downward, until the detent u'' engages the catch w' , and bends the detent plate v into a slightly inclined position, thus releasing the detent plate from the catch w' so that the piston rod will be free to start its instroke action, under the influence of the spring n , when the strain on the pull chain x is released, the collar u and the crank arm u' then returning under the influence of the spring w'' to their normal position.

The instroke of the piston rod is effected by the pressure of the spring n against the piston m , but the action of this spring is resisted by the air check between the piston and the cylinder head j , until the air forming the check is forced out through the exhaust port l . When the air pump t is employed to cause the outstroke of the piston rod, the latter freely slides through the collar u , which, during such movement, remains in its normal position. When the piston rod is at the limit of its outstroke, the catch w' engages, as in the former case, with the detent plate v , and is held, by such engagement, in its outstroke position until it is released either through the agency of the pull chain x or by the operation of the air pump t . In the latter case, the plunger r' is pressed to open the valve r , and thus relieve the air check in the cylinder, and the air pump t is then reversed to create a sufficient suction in the air duct and cylinder to draw the piston in the direction of the cylinder head j , thus disengaging the catch from the detent plate; the catch being so formed that it will permit of such disengagement.

In Figs. 1 and 2 the stop-cock c is extended beyond both sides of the casing f ,

and secured to it, in addition to the arm g , is a ratchet wheel y , having a ratchet tooth y'' . The ratchet wheel turns with the stop-cock, and fastened to the casing f is a spring pawl y' which engages with the tooth y'' and prevents the reverse rotation of the ratchet wheel and the stop-cock, while the spring pawl y' is so engaged with the ratchet tooth, thus holding the stop-cock in its open position. To manually release the spring pawl y' from the ratchet tooth y'' , the stem c' of the stop-cock is extended beyond the ratchet wheel, and loosely mounted thereon is a hub z rotatable independently of, and movable laterally toward and away from, the ratchet wheel; the hub z having a lever arm z' by which the stop-cock may be manually actuated and an offset z'' normally engaging the pawl y' and in contact therewith by a tension spring a' , which presses the hub z into contact with the ratchet wheel y .

The operation of the air pump t causes the outstroke movement of the piston rod and the turning of the stop-cock c to open the passage through the pipe b to the burner as above described, and as the ratchet wheel y turns in unison with the stop-cock, this will bring the ratchet tooth y'' into engagement with the spring pawl y' to hold the valve open; but no corresponding movement of the lever z' and hub z will occur as the lever is maintained in its normal position by the tension spring a' , which is so arranged as to not only press it against the ratchet wheel but also to hold it inoperative as shown in full lines in Fig. 1^a, with the offset z'' in contact with the pawl y' .

The engagement of the ratchet tooth y'' with the pawl y' holds the piston and rod in their outstroke position, and the stop-cock open, until the pawl y' is released from the ratchet tooth. The release of the pawl y' from the ratchet tooth y'' may be effected either by a pull chain, connected with the lever z' or by the reverse operation of the air pump, as above described. In the case of the pull chain, the lever z' and hub z are turned until the offset z'' comes into contact with the pawl y' and presses it away from the ratchet tooth y'' , the piston rod and piston, under the influence of the spring n , then being free to move in the direction of the cylinder head j , and close the stop-cock as above described, when the strain on the pull chain is released. This turning movement of the lever z' and the hub z brings the offset above the top of the pawl y' , which, as shown in Fig. 8 has an inclined side d' in the path of the offset so that, when the lever and hub reverse their movement, under the influence of the tension spring, the engagement of the offset with this inclined side will press the hub z laterally from the ratchet wheel and enable the offset to clear 130

the pawl y' on the completion of its return movement. When the offset clears the pawl, the tension spring a' presses the hub z again into contact with the ratchet wheel 5 and brings the offset z'' again into operative relation with the pawl.

When it is desired to manually open the stop-cock, c , the lever is turned by the pull chain x from the position shown in full lines 10 in Fig. 1^a to the position shown in dotted lines in the same figure. This turning movement of the lever and hub brings a clutch member e' on the hub z into engagement with a clutch member e'' on the ratchet 15 wheel y , causing the turning movement of the ratchet wheel and stop-cock, in unison with that of the hub z , until the stop-cock is fully opened, the ratchet tooth y'' then being engaged by the pawl y' . The turning 20 of the stop-cock moves with it the arm g , which operating in the slotted knuckle m' , draws the piston rod to the limit of its out-stroke, and the piston to the limit of its movement in the direction of the cylinder 25 head j' , as above described. When the strain on the pull chain x is released, the lever z' and hub z return to their normal position, under the influence of the tension spring a' , as previously described in connection 30 with the closing of the stop-cock. When the pull chain is operated to release the pawl from the instroke of the piston rod, the spring n , presses the piston toward the cylinder head j , the action of the spring being resisted by the air check within the air 35 cylinder. This air check, owing to the exhaust port being regulable through the adjustment of the cap l' or other equivalent mechanical means, will predetermine the 40 length of time required for the closing movement of the stop-cock. Thus it is possible for a person desiring to extinguish the light by the pull chain to leave the premises before the illumination ceases.

45 The detent pawl y' is formed with an offset f' against which the ratchet tooth y'' engages when the stop-cock is open, the offset f' being slightly inclined outwardly from the tooth, and the tension of the detent pawl 50 y' being sufficient to continually engage the ratchet tooth y'' and hold the stop-cock open until released from the ratchet tooth, either manually, by the use of the pull chain, as above described, or through the 55 action of the air pump. When the air pump is employed to release the ratchet tooth from the pawl y' , its action is reversed when the plunger r' has been pressed to open the valve r , the pressure of the air 60 check in the air cylinder then being relieved and a sufficient suction created in the air duct and cylinder to draw the piston in the direction of the cylinder head j , and bring the slotted knuckle m'' into engagement.

with the arm g , during the corresponding 65 instroke of the piston rod, this suction applying sufficient force to the arm g and stop-cock to cause the ratchet tooth, by its engagement with the inclined offset f' , to spring the pawl y' free from engagement 70 with it.

Should it be desired to dispense with the use of the air pump and the air duct for the operation of the apparatus and to rely solely upon the use of the pull chain for the actuation of the parts, the inlet port k will, in that case, be provided with a check valve k' , which will permit of the admission of air through the inlet port to the air cylinder and prevent its escape therefrom.

In the use of the apparatus the gas at the burner of the gas light fixture can be instantly ignited and extinguished from any station with which the air duct of such gas light fixture is connected, thus rendering it 85 possible to control the illumination furnished by the gas light fixture at any distance therefrom. When an actuator such as the pull chain and ratchet arrangement, shown in Figs. 1 and 2, or the pull chain, 90 crank arm, detent plate, and detent, shown in Fig. 3 is employed to turn the stop-cock, the gas can be manually ignited and extinguished by the operation of such actuator, and, the air check in the air cylinder, 95 the escape of which is regulable through the exhaust port, will determine the length of time elapsing between the extinguishing operation of the actuator and the closing of the stop-cock.

From the foregoing description of the construction and operation of the apparatus, it can be ascertained; that the air cylinder, with its inlet, exhaust and relief ports, and the spring pressed piston and rod constitute 105 an air check controlling the action of the stop-cock, that the air pump with its air duct, whether employed independently of, when used with a single gas light fixture, or, in conjunction with an air chest, having 110 valve controlled connections for several gas light fixtures; constitute a pneumatic actuator for the air check; that the spring tensioned ratchet and lever mechanism shown in Figs. 1 and 2 or the spring tensioned 115 crank arm and collar shown in Fig. 3; constitute a mechanical actuator for the air check; and that the air check may be operated by either the pneumatic or mechanical actuator, and that such operation of the air 120 check may be reversed at will by the other actuator, and from the foregoing description it will also be ascertained that the details of the construction and operation of the parts may be varied within the scope of 125 the claims without departing from the essential principles of the invention.

Having thus fully described my invention,

what I claim as new and desire to secure by Letters Patent is—

1. In a gas lighting and extinguishing apparatus, including a gas burner and a stop-cock governing the flow of gas thereto, an air check controlling the movement of the stop-cock, said air check comprising a piston, a cylinder for said piston having a relief port through which the air in the cylinder between the piston and cylinder head may escape during the outstroke of the piston, and a relief port interjacent the cylinder heads to partly relieve the pressure in the cylinder between the piston and the opposite cylinder head for a partial instroke of the piston, and operating means for the stop-cock actuated by the piston.
2. In a gas lighting and extinguishing apparatus, a controlling means, for the stop-cock of a gas burner, comprising a cylinder, a piston therein, a piston rod for the piston extending beyond the cylinder to actuate the stop-cock, said cylinder having a relief port through which the air in the cylinder, between the piston and cylinder head, may escape during the outstroke of the piston, and a relief port interjacent the cylinder heads to partly relieve the pressure in the cylinders between the piston and opposite cylinder head for a partial instroke of the piston, and means for actuating the piston.
3. In a gas lighting and extinguishing apparatus, comprising a gas burner and a stop cock therefor, the combination of an air cylinder, a piston therein controlling the movement of the stop cock, a spring causing the movement of the piston in one direction, pneumatic means connected with the air cylinder for creating pressure thereon to move the piston in the opposite direction, and means preventing the movement of the piston under the influence of the spring until a subsequent operation of the pneumatic means.
4. In a gas lighting and extinguishing apparatus, comprising a gas burner and a stop cock therefor, the combination of an air cylinder, a piston therein controlling the movement of the stop cock, a spring causing the movement of the piston in one direction, pneumatic means connected with the air cylinder causing the movement of the piston in the opposite direction, and a detent to hold the stop cock in open position rendered operative by the action of the piston to open the stop cock, and rendered inoperative by the action of the pneumatic means.
5. In a gas lighting and extinguishing apparatus, comprising a gas burner and a stop cock therefor, the combination of an air cylinder having inlet and relief ports, a piston movable within the cylinder controlling the opening and closing movements of the stop cock, means for actuating the piston, and detent means to hold the stop cock in open position released by a partial actuation of the piston when positioned to hold the stop cock open.
6. In a gas lighting and extinguishing apparatus, comprising a gas burner and a stop cock therefor, the combination of an air cylinder, a spring-pressed piston within the air cylinder actuating the stop cock, pneumatic means connected with the air cylinder causing one movement of the piston and controlling its other movement for the opening and closing of the stop cock, detent means preventing the reverse movement of the piston, and means for releasing the detent means for the closing of the stop cock.
7. In a gas lighting and extinguishing apparatus, including a gas burner, a stop-cock therefor, and an arm for the stop-cock, by which it is turned to govern the flow of gas to the gas burner, the combination of an air cylinder having inlet and relief ports, a piston within the air cylinder, means for creating pressure within the air cylinder for one movement of the piston, a spring effecting the opposite movement of the piston, and means actuated by the piston for moving the arm and stop-cock.
8. In a gas lighting and extinguishing apparatus, a gas burner, a stop-cock therefor, an arm for the stop-cock, by which it is turned to control the flow of gas to the gas burner, an air cylinder, a piston therein, a piston rod for the piston actuating said arm, pneumatic means connected with the air cylinder, forcing pressure into the cylinder to effect the action of the piston for one movement of the stop-cock, a spring for the piston effecting its opposite movement for the other movement of the stop-cock, and detent means to hold the stop-cock in open position, released by a partial actuation of the piston when positioned to hold the stop-cock open.
9. In a gas lighting and extinguishing apparatus, the combination of a gas burner, a stop cock therefor, an air cylinder, a piston within the air cylinder, a piston rod for the piston, an arm for the stop cock connected with the piston rod whereby the movement of the piston may open and close the stop cock, means connected with the cylinder for causing one movement of the piston, a spring within the cylinder for causing its other movement, and a releasable detent for holding the stop cock in open position.
10. In a gas lighting and extinguishing apparatus, including a gas burner, a stop-cock therefor, and an arm for the stop-cock, by which it is turned to govern the flow of gas to the gas burner, the combination of an air cylinder having inlet and relief ports, a piston within the air cylinder, means for creating pressure within the air cylinder for

one movement of the piston, a spring effecting the opposite movement of the piston, and means actuated by the piston for moving the arm and stop-cock, and detent means to hold 5 the stock-cock in open position, released by a partial actuation of the piston when positioned to hold the stop-cock open.

11. In a gas lighting and extinguishing apparatus, the combination of an air cylinder having inlet and relief ports, a spring-pressed piston within the air cylinder, a piston rod for the piston, a detent for holding the piston rod at the limit of its outstroke, pneumatic means for creating and relieving pressure in the air cylinder for the operation 10 of the piston, and mechanical means for actuating the piston, either of which may be used independently of the other to effect the 15

movement of the piston and release the detent means.

12. A gas lighting and extinguishing apparatus, comprising an air cylinder, having inlet and relief ports, a spring pressed piston within the air cylinder, a piston rod for the piston, detent means for holding the piston, and rod at the completion of their outstroke, and pneumatic means for selectively creating pressure and suction in the air cylinder and releasing the detent means for the instroke of the piston and rod. 20 25 30
